UNITED STATES PATENT OFFICE.

WILLIAM A. BROWN AND JOHN BRANNAN, OF DENVER, COLORADO.

CHAIN-GRADE-SUPPORTING STRUCTURE.

1,295,685.

Specification of Letters Patent. Patented Feb. 25, 1919.

Application filed November 7, 1917. Serial No. 200,774.

To all whom it may concern:

Be it known that we, WILLIAM A. BROWN and JOHN BRANNAN, citizens of United States residing at Denver, in the county of Denver and State of Colorado, have invented certain new and useful Improvements in Chain-Grate-Supporting Structures; and we do hereby declare the following to be a full, clear, and exact description

10 of the invention, such as will enable others skilled in the art to which it appertains to make and use the same.

This invention relates to chain grates and more particularly to supporting structure 15 therefor and has for an object to provide a new and improved structure for supporting a chain grate of any desired or usual and ordinary type whereby the tendency of the usual transverse carrying rollers, the rear 20 sprocket shaft and its cross beam to sag because of the heat, is eliminated.

A further object of the invention is to provide a new and improved grate support which facilitates operation of the grate, and 25 another object is to improve grate structures so that removal and renewal of parts may be readily accomplished.

With these and other objects in view, the invention comprises certain novel constructions, combinations and arrangement of parts as will be hereinafter more fully described and claimed.

In the drawing:

Figure 1 is a side elevation of an improved support,

Fig. 2 is a transverse sectional view taken on line 2--2 of Fig. 1;

Fig. 3 is a view in end elevation as indicated by arrow 3 at Fig. 1;

Fig. 4 is a view in end elevation of a chain grate having a number of parallel belts and showing the intermediate longitudinal supports for the rollers and sprocket shafts,

Fig. 5 is a plan view of the supports of a part of the grate shown in Fig. 4,

Fig. 6 is a vertical, transverse section of a single belt grade with intermediate supports for the shaft and rollers,

Fig. 7 is a similar view showing a grate of two belts in combination with the improved intermediate support.

A serious defect with chain grates is the

tendency they have to sag and bind because of the bending of the transverse main and 55 roller supports. It has been proposed to rest the back sprocket shaft and the rollers upon narrow devices supported at the sides of the grate but these transverse supports eventually warp and thus throw the parts out 60 of alignment and render the grate inoperative.

Therefore a primary feature of this invention resides in a means which, while it may be subjected to the heat, is of such construction and disposition as to be thoroughly practicable, substantial and lasting. At the same time it facilitates the operation of the grate and is easily kept in repair.

There is shown in Fig. 6 a form of chain 70 grate of ordinary construction having a belt A of bars.

The improved grate supporting structure which forms the subject matter of this application comprises a longitudinal beam 10 75 disposed between the parallel belts of a chain grate A. Upon the beam 10 are positioned spacers 11, preferably in the form of hollow sleeves and beams or spacers 12 of channel or like construction, which may be 80 provided with bearings as 12' for shaft B.

Upon the spacers 11 and 12 is secured a plate 13^a carrying parallel spaced angle irons 13 and such angle irons, spacers and beams are connected together in any approved manner as by the use of bolts 14.

Clamped end to end between the angle irons 13, a plurality of upright plates 16 are employed, being secured in any approved manner as by the bolts 17. The 90 blocks intermediate the ends of the structure which are subjected to the greater heat and therefore require a greater amount of repair are made in comparatively short lengths and interchangeable so that they 95 may be replaced at any time quickly, conveniently and cheaply. The end plates 18 and 19 are also similarly bolted between the angle irons but by reason of the requirement of the ends of the structure, do not correspond to the intermediate blocks.

The angle irons 13 are provided with journal bearings 20 while the beam 10 is likewise provided with journal bearings 21 in which are journaled the inner ends of 105 rollers 22 carrying the traveling grate struc-

ture on both its upper and lower stretches. The lower corners of the plates 16 are cut away to clear the upper rollers.

The grate structure, in the present instance, is indicated conventionally at A in Fig. 3 and by dotted lines at A in Fig. 4. It is intended to represent any usual and ordinary type of traveling grate structure and sprockets 25 are employed to correspond to the mechanism of the grate structure, the sprockets shown in the drawing being only indicative.

An entire central support as thus described is mounted upon rollers 26 which in turn, operate upon rails 27 secured to the bottom of the ash pit and extending out into the fire room so that it may be readily moved out into the fire room for the purpose of repairs.

20. The present intermediate support makes possible the use of comparatively short rollers 22 which have been found to be points of weakness in ordinary traveling grate structures where long transverse rollers and 25 shafts are employed and supported only at the side of the grate and which become warped and buckled from the action of the heat. The several flights of grate bars are also separated by the plates 16 so that each 30 flight may be driven at an independent speed as may be found desirable by reason of its location in the fire box or other necessities of fire, and the adjacent ends of the bars are prevented from interlocking. The 35 plates 16 projecting up between the inner ends of the bars of a grate A not only serve to guide and aline the bars but also fill the space necessary to prevent the bars from jamming and also prevent coals from falling between the grate ends. An entire grate 40 may consist of as many parallel belts as may be desired, each belt being supported, at its edge adjacent another belt, upon a support preferably as described.

45. We have hereinbefore described the grate supporting rollers as having their ends journaled in our improved supporting members. In this regard we wish to explain that in some grates these rollers consist of a solid 50 core or rod fixedly mounted at each side of the grate with a rolling or revolving sleeve thereon. In case of such construction the rod or core need not be cut but many may be solid and continuous from one side of the 55 grate to the other, passing through our supporting members at the point indicated in the drawings for the journaling of the ends of the rollers. In such a case the revolving sleeve which constitutes the roller 60 proper may have its ends revolvably journaled in our improved supporting members or may be cut short thereof and the journaling eliminated, the roller in such case gaining its support simply from the passing 65 of the core or rod through the im-

proved supporting members. The form of the construction at this point is immaterial as the construction of our improved support will be the same in substance in either case.

What is claimed is:

1. A traveling grate support comprising a central track and a longitudinal girder structure movable thereon, the structure provided at its top with upright guide plates for the adjacent end of grate bars, 70 and sprocket shafts and idler rollers journaled intermediately of the width of the grate in said supporting girder.

2. A traveling grate support comprising spaced sprockets and their shafts, transverse 80 carrying rollers arranged between the sprockets, a central carriage arranged longitudinally of the grate and supporting the shafts and said rollers, a track, and wheels for the carriage bearing upon the track facilitating bodily movement of the assembled parts.

3. A chain grate having, in combination, a plurality of parallel belts of bars; chain sprockets and their shafts, and supporting 90 rollers arranged between the sprockets to support the belts; and a central carriage between the adjacent edges of the belts in which the shafts and rollers are journaled, the carriage having an upright filler and 95 guide between the adjacent ends of the grate bars.

4. A chain grate having, in combination, a plurality of parallel belts of bars; chain sprockets and their shafts, and supporting 100 rollers arranged between the sprockets to support the belts; and a central carriage between the adjacent edges of the belts in which the shafts and rollers are journaled, the carriage having an upright filler and 105 guide between the adjacent ends of the grate bars, the filler terminating at the top plane of the belts.

5. A chain grate having, in combination, a plurality of parallel belts of transverse 110 grate bars; carrying sprockets and their shafts; supporting rollers mounted at intervals between the sprockets to prevent sagging of the belts, a carriage between the adjacent edges of the belts and journaling the 115 shafts and the adjacent ends of the said rollers.

6. A chain grate having in combination, a plurality of parallel belts of grate bars, carrying sprockets and their shafts, supporting rollers located at fixed distances between the sprockets to support the belts, a longitudinal girder structure between the adjacent edges of the belts and supporting the sprocket shafts and the adjacent ends of said 125 rollers, and means for supporting said structure.

7. A chain grate having in combination, a plurality of parallel belts of grate bars, carrying sprockets and their shafts, support- 130

ing rollers upon and over which the belts travel, a longitudinal girder structure between the adjacent edges of the belts in which the sprocket shafts and the ends of 55 said rollers are journaled, and means beneath said structure for supporting the same.

8. A chain grate having in combination, a plurality of parallel belts of grate bars, 10 carrying sprockets and their shafts, supporting rollers to carry the belts, a longitudinal girder structure between the adjacent edges of the belts, and means for movably supporting said structure, said girder journaling the sprocket shafts and rollers. 15

9. A chain grate having in combination, a plurality of parallel belts of grate bars, carrying sprockets and their shafts, supporting rollers to carry the belts, a longitudinal girder structure between the adjacent edges 20 of the belts and upon which said shafts and rollers are journaled and means for supporting said structure, said girder provided with a partition comprising a plurality of interchangeable plates interposed between 25 the adjacent ends of the grate bars.

In testimony whereof we affix our signatures in presence of two witnesses.

WILLIAM A. BROWN.
JOHN BRANNAN.
